ABSTRACT

String shot apparatus and method of servicing perforated well casing using one or more explosive cords supported along a wire line and equipped with discriminator means for detonating the cords independently or in groups at the operator's option. The wire line includes centralizers designed to be quickly assembled to and detached from the line as well as means for securing the explosive cord to the line in a desired degree of tautness. The explosive cord includes means for eliminating stretch and preferably embodied therein to safeguard against its elongation, ballooning, and looping by frictional or other forces and temperature rise encountered during the servicing operation. A readily opened and closed blowout protector is securable across the well head to seal the well closed about the wire line to avoid a blowout if the servicing operation releases high-subsurface pressures into the well.

**METHOD OF CONDUCTING STRING SHOT
OPERATIONS IN AN OIL WELL**

This application is a division of my application for United States Letters Patent Serial No. 27,214, filed Apr. 10, 1970, and now U.S. Pat. No. 3,572,245.

This invention relates to string shot apparatus and more particularly to an improved method for performing a cleaning and reconditioning operation in a well using one or more explosive cords and including means for activating one or a series of string shot operations carried out at any desired time intervals during a single wire line "run-in" operation.

The string shot technique employed to perform servicing operations in oil wells and to improve the flow by clearing away material tending to clog the flow perforations is subject to many shortcomings and disadvantages avoided by the present invention. This technique utilizes an explosive cord supported along the side of a wire line and lowered to position the cord opposite a section of perforated casing to be cleared of debris. It is not possible to determine the cause or seriousness of the clogged condition and more particularly how strong an explosive charge is required to clear the perforations yet avoid risk of damage to the casing. It is costly and time-consuming to carry out a string shot operation and this encourages the operators to use an excessively powerful charge to avoid having to perform several run-in operations. Not infrequently, the extra strong charge seriously damages the casing.

Attempts to use explosive cords of low power or strength are uncertain and often result in failure or produce serious damage to the casing or parting of the wire line and loss of the weight required to pull the line into the well for quite different reasons. For example, in certain instances the cords malfunction or fail to explode or explode over only a small portion of their full length due to a failure of flame or shock propagation along the cord. For reasons that have not been understood prior to the present invention, these lower strength lines would explode over only a short portion of their upper lengths. In other instances either the wire line was severed or serious damage caused to the casing, or both, for reasons not understood or readily explained. It has been discovered that, in most instances, these accidents are produced in various ways including in particular stretching, ballooning and looping of the cord due to a number of factors including axial shifting of the wire line centralizers or other anchorage securing the cord to the wire line, the adverse effect on the cord of the very substantial sub-surface ambient temperatures customarily encountered at lower levels in oil wells and the high drag forces acting on the cord as it is lowered through the mud and other fluids customarily present in a well. As a result of this stretching or the shifting of the cord anchorage the distance between adjacent grains leads to propagation failure. It can also result in excess portions of the stretched cord ballooning laterally close to or against the casing and, under more extreme conditions, collecting in a loop adjacent an anchorage connection between the cord and the wire line. Upon detonation of the balloon or loop, or both, an unusually powerful blast is produced in a localized area of the well which not infrequently cuts the wire line and releases the line weight but can cause serious damage to the casing itself.

It has been proposed heretofore to assemble a pair of explosive cords in parallel along the wire line and to explode them separately either by using a single or separate pairs of electrical leads. If the same pair is used, then both cords are set off in fast unregulatable sequence. The use of separate lead wires for each explosive cord enables the operator to vary the interval between detonations but is subject to the serious disadvantage of having to provide and protect separate leads for each charge. This complicates the equipment and servicing operation and involves the risk of severing one or more of the lead-in wires and greatly increases the risk of malfunctions as well as the maintenance and handling costs.

Other problems associated with string shot operations as heretofore conducted involve the problem of equipping the wire line with the centralizer devices to hold the line out of

contact with the casing sidewall and couplings during the run-in and pullout cycle as well as to safeguard the explosive cord against damage during the lowering operation. These centralizers are required at frequent intervals along the wire line and their presence on the line interferes with reeling and storage of the line.

The foregoing and other serious disadvantages accompanying string shot operations as heretofore conducted are avoided by the present invention using the equipment and the improved techniques provided by this invention. A simple wire line is employed having a central conductor and a second conductor comprising the metallic sheath of the line which are utilized to supply the electrical energy required to detonate one or a series of explosive cords in any desired time interval or simultaneously in one or more groups if so desired. Explosive cord incorporating means safeguarding against stretch and malfunctioning of the cord and retarding temperature rise of the explosive itself makes possible the use of lower explosive strength cord than heretofore possible and numerous other advantages.

An improved centralizer construction permits the centralizer to be installed and removed from the wire line expeditiously at the well head. After the main body of the centralizer has been detached, the wire line can be compactly reeled on the takeup spool or storage reel. As soon as the centralizer is installed on the wire line one or more lengths of explosive cord can be secured to the periphery of its main body following which the wire line is lowered into the well until in position to receive the next centralizer.

The selective detonation of explosive cords via a single pair of conductors is made possible by unique electrical discriminator means connected between one of the conductive paths and the detonators for each cord. Typically the discriminator utilizes semiconductors arranged to pass electrical energy only to a particular cord or to a set of cords selected for detonation at a particular time. Greater versatility is achieved by utilizing the discriminator in combination with a reversing switch and means for controlling the applied potential.

Another feature of the invention is the provision of a blowout protector of simple unique design across the well-head. This protector includes a cover having a nonconductive gasket which fits tightly about the wire line in the closed position of the protector and which opens for the full diameter of the casing whenever the wire line is being lowered or withdrawn.

Accordingly, it is an object of the present invention to provide a unique, improved method for conducting string shot operations in a well in such manner as to safeguard against ballooning and looping of the explosive cord during lowering of the same into a well.

Another object of the invention is the provision of a method for lowering multiple string shots simultaneously into a well in a manner safeguarding against ballooning and looping of the several string shots and for separately detonating said string shots at will during a single wire line run-in operation.

Another object of the invention is the provision of a method utilizing a two-conductor wire line to detonate one or more string shots simultaneously or in any desired order and time intervals.

These and other more specific objects will appear upon reading the following specification and claims and upon considering in connection therewith the attached drawing to which they relate.

Referring now to the drawing in which a preferred embodiment of the invention is illustrated:

FIG. 1 is a vertical sectional view of a well having a perforated casing and showing an illustrative embodiment of the invention string shot apparatus in position for detonation of its separate cords;

FIG. 2 is a top plan view on an enlarged scale of the blowout protector closed against the wellhead;

FIG. 3 is a cross-sectional view taken along line 3-3 on FIG. 2;

FIG. 4 is a cross-sectional view taken along line 4—4 on FIG. 3;

FIG. 5 is a diagrammatic elevational view at the wellhead showing details of the means for installing the explosive along the wire line at a desired uniform tension;

FIG. 6 is a schematic view of an illustrative embodiment of the electrical firing circuit for a plurality of explosive cords;

FIG. 7 is an elevational view on an enlarged scale of means for securing the explosive cords to an adjacent portion of the wire line;

FIG. 8 is a cross-sectional view taken along line 8—8 on FIG. 7;

FIG. 9 is a fragmentary enlarged view of the explosive cord;

FIG. 10 is an elevational view of one preferred embodiment of the wire line centralizer;

FIG. 11 is a top plan view taken on FIG. 10;

FIG. 12 is a cross-sectional view taken along line 12—12 on FIG. 10; and

FIG. 13 is an elevational view of a second preferred form of the centralizer assembled to the wire line.

Referring initially and more particularly to FIG. 1, there is shown an oil well casing 10 having a multiplicity of flow perforations 11 distributed along its sidewall at the production flow level. It will be understood that these perforations may be distributed over many feet of the casing and in one or more areas of the casing. Secured to the top of the casing is a radial flange 12 to which a blowout protector mounting ring 13 is detachably secured, as by bolts 15. This ring has a central opening 16, corresponding to the I.D. of the casing so as not to restrict the entrance to the well. Opening 16 is provided with a cover 17 here shown as formed in a single part and equipped with a hinge 18 secured to mounting ring 13. However, it will be understood that cover 17 may be formed in two halves each having its own hinge connection with mounting ring 13 if so desired. Threaded studs 20 welded or otherwise secured to mounting ring 13 pass through openings in cover 17 and support thumb nuts 22 for clamping the cover firmly sealed closed prior to a string shot firing operation.

Suitably secured to cover 17 and mounting ring 13 is a two-part or split sealing gasket 23,24 having its edge portions shaped to clamp snugly about the wire line 25 when cover 17 is closed. Each of the gasket halves 23,24 are suitably and firmly anchored to the cover and to the mounting ring as in the manner indicated in FIGS. 2 and 4. These nonconductive sealing gaskets not only provide a fluidtight seal about the wire line but isolate the line and its conductors electrically from the casing.

Wire line 25 includes a central conductor 26 separated from the helical sheath conductors 27 which also serve as the second conductive path employed as will be explained presently to provide one portion of the electrical circuit between the direct current power source 28 (FIG. 6) and one or more string shots. Typically wire line 25 passes over a guide pulley 30 overlying the well and thence to a storage reel, not shown, but of any suitable well-known construction driven by reversible power means for handling the wire line.

Referring now more particularly to FIGS. 1, 10, 11 and 12, it will be understood that wire line 25 includes a weight 35 at its lower end of adequate size to facilitate the expeditious lowering of the wire line into the well through the thick fluids generally present in the well. Distributed along the lower portion of the wire line at suitable intervals, as 10 to 25 feet, are a plurality of centralizers 40,40. As is best shown in FIGS. 10 to 12, each centralizer includes a mandrel 41 having a diameter similar to that of wire line 25 and provided at its opposite ends with enlargements such as yokes 42. These yokes are formed with aligned openings 43 each equipped with a pivot pin 44 suitably secured in place and extending through a loop 45 of the wire line or of a similar cable 46 interconnecting adjacent ones of the centralizer mandrels.

Loosely fitting over the midportions of mandrels 41 is the main body 48 of the centralizer. This main body is generally cylindrical in contour and has a long deep slot 49 opening through one sidewall and sized to fit readily over mandrel 41.

Main body 48 is slightly shorter than the distance between the adjacent ends of yokes 42, and is formed with a threaded bore seating a thumb screw 50 having a knurled head. Its inner end extends into slot 49 in position to engage the mandrel and hold the centralizer body firmly locked in assembled position in the manner made clear by FIG. 12.

Extending crosswise of the opposite ends of the centralizer bodies 48 are pairs of passages 51 loosely seating highly tempered wire loops 53. As herein shown, each centralizer is provided with a single pair of these wire loops shaped as best shown in FIG. 10 and each including oppositely directed semicylindrical loops projecting radially from the sidewall of main body 48. Since each of these loops lies at an angle to the portions located in passages 51, the loops are held against sliding movement lengthwise of these passages. The radial extent of each of the loops is such that they cooperate in holding the wire line loosely centralized in the well casing.

A second and simpler embodiment of the invention centralizer 40', illustrated in FIG. 13, may be mounted directly on wire line 25 at any suitable spacing therealong. For this purpose the wire line is provided with enlargements, such as collars 60, telescoped over one end of the wire line and then subjected to high-pressure contraction forces adequate to squeeze the ductile collar material into interlocking gripping action with the wire sheath of the wire line. It will also be understood that the collars may be brazed or otherwise firmly secured to the wire line. These collars pass readily over the storage reel for the wire line.

The main body 48' of the centralizer is formed with slot 49' similar to the corresponding slot in FIGS. 10 and 12 and sized to fit readily over the wire line. Intermediate the opposite ends of this slot there is an enlarged U-shaped recess 61 shaped to fit loosely about and accommodate collar 60 in the manner made clear by FIG. 13. A thumb screw 50' is carried in main body 48' and serves similarly to the corresponding thumb screw in FIGS. 10 to 12 to hold the centralizer assembled to the wire line. Additionally main body 48' is equipped with wire loops 53' in the same manner described above in connection with FIGS. 10 to 12. It is therefore evident that the thumb screw 50' holds the centralizer detachably assembled to the wire line whereas collar 60 cooperates with recess 61 to hold the centralizer against movement longitudinally of the wire line. The simplified centralizer avoids the need for the yoke-equipped mandrels as well as for separate lengths of cabling 46 interconnecting adjacent centralizers.

The assembly of the explosive cord through the wire line will now be described with the aid of FIGS. 1 and 5. The crew attaches weight 35 to the lowermost end of the wire line and inserts this weight into the top of the well. As shown in FIGS. 1 and 5, only a pair of explosive cords 65,66 are shown. In many operations a single pair suffices but in other it may be desirable to fit the wire line with a larger number of string shots. In this case, it is usually preferable to use explosive cord of considerably smaller size and explosive power than that heretofore employed. For example, it has been common practice heretofore not to use explosive cord smaller than 25 grain size in string shot operations. However, by this invention, it is feasible and advantageous to use cord of the smallest commercial size, namely 4 grain as well as various sizes intermediate 4 grain and 25 grain provided adequate precautions are taken against elongation of the cord while being lowered into the well. Such precautions may comprise firm anchorage of the cord to the wire line at closely spaced intervals and/or the use of cord in accordance with the present invention incorporating builtin stretch resisting means such as nonstretching small wires or other high-strength nonstretching filaments 68,68. These may take the place of a corresponding number of filaments of the outer protective sheath of the cord in the manner shown in FIG. 9. As there shown, the nonstretching filaments 68 are wrapped spirally in opposite directions between adjacent spiral wrappings 69,69 of the conventional cord sheath. It will be understood that the explosive cord is otherwise of any suitable conventional design including a central core of

explosive material 70 encased within a tough flexible tubular shroud 71 of plastic or the like. The latter is embraced by the wax-covered braided sheath 69,69.

Desirably, the explosive core 65,66 is assembled lengthwise of the wire line in a taut condition and preloaded to a suitable uniform tension. According to this invention, this is accomplished in the manner illustrated in FIG. 5 and showing the tensioning equipment for one only of the cords, it being understood that cord 66 passes over similar automatic tensioning equipment. The cord passes from a supply reel 73 mounted on a suitable support 74, and thence over an idler pulley 75. The cord is held firmly seated on pulley 75 by a pivotally supported idler pulley 76 and a tension spring 77. The cord then passes over a pair of idlers 78 between which there is mounted a pulley 79 on which any suitable member of removable tension-regulating weights 80,80 can be mounted. The cord then passes over an idler 82 carried by the hanger 83 for wire line guide pulley 30, pulley 82 being appropriately positioned close to one side of the wire line at the point of entry into the well head.

It will be understood that the wire line leaves the power-driven wire line reel carrying only mandrels 41 or their equivalent such as collars 60 (FIG. 13). As these components approach entry into the well head, the wire line is stopped while the crew inserts the main body 48 or 48' of the centralizer and secures it in place by tightening thumb nut 50 or 50'. At the same time the explosive cords are securely anchored to the main body of the centralizer by serving the same tapes or tie-bands 85 (FIG. 1). The crew then proceeds to lower the wire line along with the attached explosive cords under appropriate tension as determined by the weights 80 carried by the pulley 79. Centralizers continue to be assembled to the wire line in succession and anchored to the explosive cords as described.

If the centralizers are spaced considerable distances apart or in cases where smaller size explosive cord is being used, it is desirable to anchor the cords to the wire line at one or more points between adjacent centralizers. This is done using cylinders 90 constructed as shown in FIGS. 7 and 8. These anchor members are secured to the wire line by swaging, brazing or other suitable means. Each member 90 is formed with long grooves 91 of V-shape in cross section extending lengthwise of the body and sized to grip cords 65,66 firmly irrespective of the particular size being used. A deep annular groove encircling the midportion of member 90 accommodates tape or banding 93 applied over the cords 65,66 to clamp the latter firmly within grooves 91.

The equipment employed in connection with the two conductors 26,27 of the wire line to detonate the explosive cords according to one preferred embodiment is illustrated schematically in FIG. 6. The upper ends of conductors 26,27 are connected to battery 28 by way of a double-throw reversing switch 95 and a rheostat 96. The lower end of the wire line closest to the upper end of the explosive cords is connected to the cord by way of an electrical discriminator 97. This discriminator preferably comprises a thick-walled tubular housing 98 of nonconductive material charged with potting compound encapsulating at least one and preferably several semiconductors 99a, 99b, connected in series parallel with one of the wire line conductors as conductor 27. The other conductor 26 is connected to a common bus 100 connected in turn to one terminal of each of the cord detonators 101. The other lead 102 of each detonator is connected to a terminal post 103 in the sidewall of discriminator 98 and connected as shown in FIG. 6 to a respective one of the semiconductors 99a,99b.

The detonators 101 are preferably arranged in vertically staggered relation as indicated in FIGS. 1 and 6 and are sufficiently spaced from one another that the detonation of one does not cause detonation of any other detonator, or the premature ignition of any explosive cord.

In some service operations only two or three explosive cords are secured to the wire line during single run in operations. In

this case, ordinary diodes may be used. However when employing a larger number of string shots, such as is indicated in FIG. 6 at 65', 66', 65'', 66'', 65''', then it is desirable to employ Zener-type diodes 99a,99b of an appropriate voltage rating to be triggered by a particular voltage applied thereto by adjusting the contactor of rheostat 96. It will be noted that diodes 99a are connected in series to pass current of a particular polarity whereas diodes 99b are connected in series with one another in a parallel circuit and are triggered to pass current only by voltage of an opposite polarity.

The operation of the equipment will now be described, it being assumed that perforations 11 of well casing 10 are plugged with sand or other debris interfering with the well flow. To remove this debris and restore full flow conditions, the service crew connects the blowout preventor assembly to the top of the well casing using assembly bolts 15 and then proceed to lower weight 35 of the wire line toward the well-head. As this weight is about to disappear into the casing the main body assembly 48 of the first centralizer is inserted cross-wise of the wire line and locked in place by tightening thumb screw 51. The selected number of string shot cords are then threaded through the tension control equipment shown in FIG. 5 and their free ends are firmly secured to the opposite sides of the first centralizer by banding 85. The wire line is then lowered into the well and successive ones of the centralizer bodies are assembled to the line and taped in place. If the intermediate cord anchorages 90, such as those shown in FIGS. 6 and 7 are employed, the explosive cords are inserted into the V-shaped slots 91 of these anchorages and taped firmly in place.

After all of the centralizers have been installed and the tensioned explosive cords have been secured to the sides of the wire line in the manner just described, their upper ends are cut off in echelon and each is provided with a detonator cap 101 and connected in circuit with a respective terminal 103 of discriminator 97. The lead wires to the discriminator and to the detonator bus 100 are also completed following which the wire line is lowered into the well until the string shots are located directly opposite the perforations to be cleared of debris. Cover 17 of the blowout preventor is then closed and locked in place by thumb nuts 22 to avoid any possibility that the string shot operations will open a high-pressure area of the earth formation into the well and initiate high-pressure flow from the top of the well.

Before closing switch 95, the operator makes certain that rheostat regulator 96 is adjusted to its upper end or a harmless position ineffective to activate any detonator. The switch is then closed and the first cord is fired by adjusting rheostat 96 downwardly until the voltage increases sufficiently to fire the first string shot 65. No one of the other string shots 66,66' or 66'' will fire because the voltage is inadequate to trigger any one of the Zener diodes 99a. The second string shot 66 will be detonated simply by shifting the rheostat in a direction to increase the applied voltage to a value triggering the upper one of diodes 99a. In this same manner the operator can proceed to detonate cords 66' and 66'' in any desired time interval by regulation of rheostat 96.

He may then proceed to detonate the remainder of the cords by returning the rheostat to its initial position and close switch 95 in the opposite direction thereby reversing the polarity of the applied voltage. The operator then proceeds to adjust the voltage in steps as before to values adequate to fire cords 65', 65'', 65'''.

Should the operator desire to fire more than one cord simultaneously, he adjusts the voltage regulator 96 to the appropriate voltage known as required to assure triggering the desired number of diodes and then closes the switch in the proper direction to trigger these selected diodes.

It will therefore be apparent from the foregoing that a highly versatile technique has been provided for performing string shot service operations on oil wells having faulty flow characteristics. The technique makes it possible to employ any desired number of string shots using the smallest available

grain rating and including a series of larger grain rating and to explode these in succession or in any desired groupings until full flow conditions are restored. The technique permits well flow tests to be conducted between individual detonations to determine the effectiveness thereof, following which additional explosions of any selected size and number may be performed or, if tests show that full flow has been restored, the servicing operation can be immediately discontinued and the wire line withdrawn from the well.

The withdrawal operation is performed after opening cover 17 and then reeling in the line until the discriminator 97 and the centralizer exit from the well head. These are removed as are successive other centralizers in a simple and expeditious manner until the withdrawal operation has been completed.

While the particular method of conducting string shot operations herein shown and disclosed in detail is fully capable of attaining the objects and providing the advantages hereinbefore stated, it is to be understood that it is merely illustrative of the presently preferred embodiments of the invention, and that no limitations are intended to the details of construction or design herein shown other than as defined in the appended claims.

I claim:

1. That method of servicing an oil well with an explosive charge to remove debris from the oil inlet performances distributed along the sidewall thereof which comprises: lowering into the mouth of the well a weighted flexible wire line equipped with a pair of electrical conductors and a multiplicity of spaced apart enlargements fixed thereto, attaching quickly attachable and detachable centralizers to said wire line from the side thereof immediately adjacent first one and then another of said enlargements as said wire line is lowered into the well and held positively against axial movement along the wire line by said enlargements and effective to hold the wire line spaced generally centrally of the well, attaching an elongated explosive cord along centralizer-equipped portions of said wire line and close to the side of the wire line so as to restrain said explosive cord against elongation and ballooning by frictional drag forces as it is lowered thru well fluid of increasing temperature, connecting one end of said explosive cord to electrical detonator means connected in circuit with said electrical conductors, and closing a power circuit through said pair of conductors and said detonator means to detonate said explosive cord after it is positioned opposite said distributed oil inlet perforations.

2. That method defined in claim 1 characterized in the steps of attaching an explosive cord to said wire line having builtin stretch restraining means, and connecting said explosive cord to the wire line at intervals therealong spaced sufficiently close together to hold said explosive cord generally centered along the well.

3. That method defined in claim 1 characterized in the steps of restraining said explosive cord against stretching while being lowered into the well by securing the same to said wire line in such manner as to utilize the strength of the wire line to prevent stretching of the explosive cord.

4. That method defined in claim 1 characterized in the step of closing the mouth of the well in a fluidtight manner about a contiguous portion of the wire line after the line has been lowered to a desired level in the well and before detonating said explosive cord.

5. That method defined in claim 1 characterized in the step of attaching a centralizer to the wire line from one side thereof immediately adjacent a selected one of said stop means before the latter passes into the mouth of the well.

6. That method defined in claim 5 characterized in the step of withdrawing said wire line after said explosive cord has been detonated and coiling the line and said spaced-apart enlargements on power-driven storage reel means, and detaching said centralizers in succession as the same emerge from the well mouth and before the emerging centralizer reaches said storage reel means.

7. In a method of performing a servicing operation in a deep earth bore subject to high earth bore temperature by detonating an elongated explosive cord along the length of the bore, said method comprising the steps of securing to the side of a

5 weighted flexible wire line means an elongated explosive cord incorporating builtin antistretching means to counteract deep earth bore temperature conditions and friction and drag forces acting thereon as said explosive cord is lowered through fluid present in the bore, applying and immovably anchoring

10 individual centralizers to said wire line means from the side thereof at spaced intervals therealong and between the opposite ends of said explosive cord as successive lengths of said wire line approach the entrance to the earth bore to hold said wire line means and said explosive cord generally centrally of

15 the earth bore providing said explosive cord means with detonator means, and activating said detonator means to detonate said explosive cord means after the latter has been adjusted to a desired zone lengthwise of the earth bore, withdrawing said wire line means from the earth bore onto

20 reeling means for said wire line means, and detaching each of said centralizers from said wire line means as successive ones thereof emerge from the entrance to the earth bore.

8. That method defined in claim 7 characterized in the steps

25 of equipping said wire line means at spaced-apart intervals along the length thereof with quickly attachable and detachable centralizer means for holding at least those portions of said wire line means contiguous to said explosive cord out of contact with the sides of said earth bore.

9. That method defined in claim 7 characterized in the steps

30 of securing spaced-apart portions of said explosive cord to juxtaposed portions of said wire line means.

10. That method defined in claim 7 characterized in the step

35 of wrapping spaced-apart lengths of said wire line means and said explosive cord with tie means to hold said explosive cord in assembled position therealong and substantially fully exposed from all sides thereof as the same is lowered into an earth bore or the like.

11. That method defined in claim 8 characterized in the

40 steps of storing said flexible wire line means on power-driven storage reel means, introducing the weighted free end of said wire line means into an earth bore to be serviced, attaching individual ones of said centralizer means to said wire line means at intervals therealong, and securing said explosive cord

45 means to the exterior of said wire line means at successive intervals spaced therealong and as additional portions of said wire line means are lowered into the upper end of the earth bore.

12. That method defined in claim 11 characterized in the

50 steps of withdrawing said wire line means after detonating said cord means and storing the line means on said storage reel means while detaching successive ones of said centralizer means as the same emerge from the earth bore thereby to facilitate reeling the line means and the compact stowage

55 thereof while moving to the next earth bore in need of a service operation.

13. That method defined in claim 7 characterized in the

60 steps of securing a plurality of the same type of said explosive cord means in parallel with one another lengthwise of said wire line means, and providing explosive cord with separate detonator means, and connecting said detonator means in circuit with electrical signal discriminator means selectively responsive to electrical energy of different distinctive characteristics to detonate said explosive cord means individually

65 and at the option of control means at the upper end of said earth bore.

14. That method defined in claim 7 characterized in the step

70 of securing said explosive cord means to said suspension line means while said cord means is held taut under tension of a selected value adequate to assure the absence of slackness therealong during said securing operation.

15. That method defined in claim 7 characterized in the step

75 of securing said explosive cord means to said wire line means without slack in contiguous lengths of said cord means and said wire line means.

16. In a method of performing a servicing operation in a well casing by detonating explosive cords supported along the side of a wire line and located centrally of and opposite a sidewall of the well casing to be serviced, that improvement which comprises: the steps of supporting a plurality of explosive cords parallel to one another along the wire line in a manner to prevent harmful ballooning and looping thereof as said cords are subjected to temperature rise and drag forces as the same are lowered into a well casing, providing each explosive cord with separate detonator means in circuit with means selectively responsive to electrical energy of different distinctive characteristics to detonate a selected one only of said explosive cords as electrical energy having one of said different distinctive characteristics is applied thereto, and applying electrical energy having the appropriate respective distinctive characteristics to said detonator means to detonate said explosive cords in sequence in any desired time-delayed pattern.

17. That method defined in claim 16 characterized in the step of utilizing detonator means in circuit with means selectively responsive to energization by electrical energy of different polarity, and energizing said detonator means in timed sequence with electrical energy of different polarity.

18. That method defined in claim 16 characterized in the step of utilizing detonator means in circuit with means selectively responsive to energization by voltages of different potential levels, and applying electrical energy to said detonator means in time-delayed sequence at said different potential levels thereby to detonate said explosive cords in time-delayed sequence.

19. That method defined in claim 16 characterized in the step of utilizing solid-state devices connected in circuit between said explosive cords and a pair of conductors forming part of said wire line.

20. That method defined in claim 16 characterized in the step of sealing the upper end of the well casing while said explosive cords are being detonated to safeguard against the expulsion of well fluid if one or more of the detonations release subsurface pressures into the well.

21. That method defined in claim 20 characterized in the steps of providing the lower end of said wire line with a plural-

ty of centralizers spaced lengthwise therealong, suspending said explosive cords alongside said wire line between successive ones of said centralizers, and securing said explosive cords to spaced points about the periphery of said centralizers to isolate the drag forces acting on the explosive cords to either vertical side of the centralizers while being lowered through the well fluid.

22. That method defined in claim 16 characterized in the step of providing a single pair of conductors extending lengthwise of said wire line, connecting all of said detonator means in circuit with the lower end of said pair of conductors, and applying electrical energy of first one and then another of said different electrical characteristics to the upper ends of said pair of conductors.

23. That method defined in claim 16 characterized in the step of securing said explosive cords to spaced points along the length of said wire line while said explosive cords are loaded in tension to a predetermined load.

24. That method defined in claim 16 characterized in the step of securing said explosive cord to said wire line while held taut thereby to safeguard against objectionable elongation of said explosive cord and the possibility of a loop forming in said cord due to the elongation thereby while being lowered into the well.

25. In a method of performing a servicing operation in a deep flooded well casing to reopen the inlet perforations by detonating explosive cord means supported lengthwise of the interior of the well casing over a length coextensive with the length of the perforated inlet section thereof, that improvement which comprises the steps of lowering taut flexible wire line means into a flooded well casing along with many rods of exposed explosive cord means secured along the side of said wire line means at spaced intervals and generally parallel thereto and anchored against looping, ballooning, tensioning and stretching effective to cause malfunctioning of said cord means or damage to the well casing when said cord means is detonated and which looping, ballooning and stretching is caused by temperature rises and by drag forces acting on said explosive cord means while lowering the same into said deep flooded well casing.
